UNITED STATES PATENT OFFICE.

FREDERICK A. CODY, OF MERIDEN, CONNECTICUT.

HYDROCARBON-LIGHTING DEVICE.

SPECIFICATION forming part of Letters Patent No. 508,812, dated November 14, 1893.

Application filed January 28, 1893. Serial No. 460,105. (No model.)

To all whom it may concern:

Be it known that I, FREDERICK A. CODY, a citizen of the United States, residing at Meriden, in the county of New Haven and State of Connecticut, have invented certain new and useful Improvements in Hydrocarbon-Lighting Devices; and I do hereby declare the following to be a full, clear, and exact description of the invention, such as will enable others skilled in the art to which it appertains to make and use the same.

This invention relates to that class of hydrocarbon lighting devices in which a reservoir is located at the level of the lamps, and pipes run down from the reservoir then across a space, as beneath a floor, then up to lamps to supply them with oil; the lamps being of the Argand style without any enlargement as a receptacle for oil around the wick.

The objects of the invention are first, to provide means for the escape of air from the supply pipe so as to prevent spurting and sputtering of the flame, and the overflow of oil; second, to regulate the delivery of oil from the primary reservoir to the secondary reservoir or leveling tank so as to maintain the oil in the latter at an even head or level and insure a full and even supply to the lamps and an unvarying light; third, to provide means for removably securing a gallery at the top of the wick tube, and for supporting the wick in the absence of the gallery; fourth, to prevent wick trimmings and other dirt from gathering in the gallery; fifth, to prevent wind from blowing directly into the gallery and causing the lamp to smoke or go out; sixth, to give proper direction to the many little currents of air admitted through the flame-spreader so that the same may join and act harmoniously with the current of air to which direction is given by the exterior form of the same flame-spreader, thus properly spreading and shaping the flame and supplying it with air to produce an intense and even white light.

To this end my invention consists in the construction and combination of parts forming a hydrocarbon lighting device, hereinafter described and claimed, reference being had to the accompanying drawings, in which—

Figure 1, represents in side elevation, partly in vertical section, the lower portion of a

room with a general view of a hydrocarbon lighting device showing a portion of my invention. Fig. 2, represents a vertical section 55 of one of my lamps. Fig. 3, shows in side elevation the body of a lamp, a wind guard above it and a gallery above that, the latter two being in position as though they had been slid up off from the lamp and separated from each other, all according to my invention.

10 represents a reservoir for containing oil, supported upon a bracket shelf 11.

12 is a distributing tank located on a level with the lamp 13 and connected therewith by 65 means of a distributing pipe 14. As the two vertical portions of the pipe 14 are of nearly equal height there is very little pressure upon the oil contained in them and bubbles of air are likely to gather in the oil, sometimes running together and forming so large a bubble as to rise rapidly carrying all the oil above it suddenly to the lamp and causing the same to overflow, because this lamp in its body portion 15 is of annular form just large enough 70 to receive the wick 16 and its carrier 17, and it has no open space above the oil so that it will not hold a spoonful of oil more than is required to saturate the wick. Therefore to accommodate any such sudden rise of the oil and to 75 permit the bubbles of air to escape I provide a sentry chamber 18 on the pipe 14 close to the lamp and rising somewhat above the level of the lamp-burner. This sentry chamber is much larger than the interior of the pipe 14, 80 and it is capable of holding any amount of oil which could be brought up by a single bubble. The chamber being provided with a small vent hole 19, the oil will rise more freely in it than in the lamp closed by the wick, and a bubble 90 of air escaping from under the oil in the broader expanse of the chamber will be freely discharged at the vent 19 while the oil will fall back into the space occupied by the bubble in the pipe, thus preventing overflow of the 95 lamp.

The delivery-pipe 20 of the reservoir 10 terminates just above the open mouth or top of the tank 12, and is provided with a valve 21 having a stem 22 extending down into the 100 tank to be engaged by the lever arm 23 of a float 24 which is pivoted at 25 to a portion of the chamber and adapted to float upon oil when it rises within the chamber.

26 is a dotted line showing the level of the lamp-burner above which level the oil in the tank should not be allowed to rise, and the float 24 is so located in the tank that when 5 the oil being consumed, descends a little below this level the latter end of the float rises and acting upon the stem 22 opens the valve 21 and permits more oil to flow from the reservoir into the tank and when the oil rises in 10 the tank to very near the level of the line 26 the float being raised thereby lowers its lever end and permits the valve 21 to close, thus stopping off the supply of oil. It will thus be seen that this device is perfectly automatic 15 in supplying oil to the lamp and in maintaining it at the proper level to fully supply the wick, and yet to never overflow either from an over supply of oil in the tank, or from air accumulating in the pipe.

20 The lamp body consists of an outer tube 15 and an inner tube 27, joined and closed at their lower ends leaving between them space for a tubular wick 16, and a tubular wick raiser 17. This raiser is made of perforated 25 sheet metal, and 30 is a toothed pinion journaled in the body 15 to engage its teeth with any vertical line of holes in the perforated raiser, and provided with any suitable handle 31 exterior to the body 15, whereby the 30 pinion may be rotated to traverse the holder and the wick contained therein, up and down for the purpose first, of inserting the wick into the body, and second, of raising the wick when its upper end is consumed in serv- 35 ice. The lower end of the wick raiser terminates at an even edge between horizontal lines of perforations, while the upper edge is formed into teeth by being cut centrally on a horizontal line of perforations, and these teeth are bent 40 inward a little in order to engage the wick and to push it upward and yet to permit the wick to be freely drawn up within the raiser. The perforations in the raiser are made in lines horizontally for the purpose of permitting 45 it to be formed with its smooth edge at one end and the toothed edge at the other end as before described and the perforations are also located in vertical lines at equal distances apart so that any or every vertical line of 50 holes is adapted to be engaged by the pinion-wheel, so that no pains need be taken in inserting the raiser within the body because the instant the raiser reaches the pinion and the pinion is worked the teeth of the pinion will 55 find a line of holes and travel in them.

32 represents a spider or bracket to the arms of which the body of the lamp is secured, and to the lower end of which the base cup 33 is screwed.

60 34 is the supply tube communicating between the sentry chamber 18 and the body of the lamp by passing up centrally through the spider 32 and then turning sidewise into the lamp body through the inner tube 27 to which 65 it is permanently joined.

The base cup 33 is perforated through the

center of its bottom and threaded at this perforation to screw upon the spider, and the tube 34 passing up centrally through the spider permits the cup to be unscrewed so 70 that trimmings from the wick which fall down through the spider into the cup may be shaken out through the perforation in the bottom of the cup around the tube 34 which is much smaller than the said perforation. The 75 supply tube 34 passing up through the cup prevents the cup being displaced and lost and by entering through the inner wall of the lamp instead of through its outside it leaves the lamp more symmetrical and ornamental 80 in finish. I extend the body portion 15 to the full height of the inner tube 27 and around this body portion I fit a gallery made of two pieces of sheet metal, the lower portion 35 being stamped into the form of the frustum 85 of a cone in the region 36, with its base upward, and its lower edge terminating in a cylindrical sleeve 37, fitted to slide closely upon the body 15; and a cover shaped into the form of the frustum of a cone in the region 90 38, its base being downward. Thence this cover extends outward in the form of a flange 39 to serve as a base upon which the chimney 40 may stand, and it is provided with the usual chimney holders 41. At the outer edge 95 of the flange 39 the cover of a gallery is bent downward and beaded at 42 over the edge of the lower portion of the gallery. The upper and lower portions beaded together at their outer edges and provided with the chimney 100 holders 41 constitute the whole of the gallery. The cylindrical portion 37 and the upper edge of the portion 38 both fit closely yet removably upon the body 15. The lower portion of the gallery in the region 36 and the 105 upper portion in the region 38 are perforated through, all over the surface of each, thus permitting air to enter within the chimney 40 to supply the flame on its outer side. The top portion of the gallery slants conically 110 away from the edge of the wick tube and extends entirely over the lower portion of the gallery to prevent the gallery from being filled with wick trimmings. As the chimney 40 must necessarily be removed when the lamp 115 is trimmed the burned edges of the wick on being scraped outward over the side 15 of the lamp will slide down the incline 38 and off from the edge of the chimney base 39, thus preventing the accumulation which in some 120 lamps smokes and causes a foul smell as soon as it becomes heated after each trimming of the lamp. To insure the entire discharge of this foul trash I make the cover of the gallery in one piece without grooves in its upper face from the upper edge of the region 38 to the bead 42. The air drawn in through the region 36 becomes a little heated while within the gallery and when it escapes to the flame from the region 38 it is in condition to aid 125 130 combustion and to preserve a large portion of the flame, represented at 43, at a white

heat suitable to give a pure white light. The gallery may be taken as a single piece off from the body 15.

44 is a shield in cup-shape with its upper edge turned inward. Its lower portion 45 is formed as a cylindrical sleeve to fit closely yet removably upon the cylindrical portion 37 of the gallery. This shield 44 is not necessarily furnished to every lamp, but when a lamp is to be located in a hallway or other locality where it is subjected to a strong current of air the shield is provided to prevent the current of air from striking forcibly against the openings in the region 36 of the gallery, thus guarding against puffing and smoking of the blaze which would otherwise be caused by wind.

46 represents a flame spreader made in cylindrical form along its body portion 47, and provided with a loose flange 48 which fits freely within the tube 27, and with fingers 49 near its lower end extending outward and also fitting freely within the tube 27.

50 is a wire cross-bar within the tube 27 as a support upon which the flame spreader stands. The flange 48 is perforated vertically all over its surface to permit an upward draft of air between the body 47 of the flame spreader and the tube 27 of the lamp body. The head 51 of the flame spreader is of peculiar form which is the result of much study and experiment. It has a square shoulder or outward extending flange 51 whose transverse diameter is about equal to the diameter of the tube 27, and the spreader is located with this flange about three-eighths of an inch above the edge of the burner tubes 15, 27. From the edge of the flange 51 the sides of the head have a concave curve 52, and the top of the head is deeply concaved. The head is perforated all around its sides and its concave form at the sides and top produces a peculiar effect as follows: The current of air passing up between the tubes 47 and 27 is deflected outward by the flange 51 as shown by dotted lines 54, and impinging against the flame 43 spreads it as shown. A little higher up the air becomes sufficiently heated to join with and feed the flame. The air drawn up within

the tube 47 is deflected outward by the concave top 53 so that it passes through the side of the head in a direction to aid upward draft of the flame and soon joins with it as shown in dotted lines 55. If the top of the head were flat at 53, and the sides were vertical at 55 the air would be driven horizontally across the current 54 and would cool off that current at the very point where it should become hot enough to join with the blaze.

The sides 52 being concave stand at a considerable distance from the blaze whereby the little jets of air from the said sides lose something of their individual force and have room to become heated before striking the blaze, so that very perfect combustion and a steady white light are the result.

Having thus fully described my invention, what I believe to be new, and desire to secure by Letters Patent, is the following:

1. The combination in a hydrocarbon lighting device of a fixed lamp; an oil distributing tank located about at the level of the lamp and open at the top; a pipe descending from the tank and rising to the lamp and communicating between the tank and lamp, and a sentry chamber connected with the pipe on the rising portion thereof near the lamp and having a vent above the level of the lamp substantially as described, whereby air rising in the pipe toward the lamp may be arrested and discharged.

2. The combination in a hydrocarbon lighting device of a lamp body having an opening up through it; a spider perforated vertically through and screw-threaded upon its body and connected by its arms with the lamp body; a cup located beneath the opening in the lamp and screw-threaded removably upon the spider body; and a supply pipe passing up through the spider and cup to the lamp substantially as described.

In testimony whereof I affix my signature in presence of two witnesses.

FREDERICK A. CODY.
